UNITED STATES PATENT OFFICE.

EDWARD LA BARRE, OF NEW YORK, N. Y., AND WILLIAM SCHUCKAR, OF WEST NEW YORK, NEW JERSEY.

AUTOMATIC TRAIN-STOP.

1,241,997.

Specification of Letters Patent.

Patented Oct. 2, 1917.

Application filed January 7, 1914, Serial No. 810,729. Renewed March 9, 1917. Serial No. 153,739.

To all whom it may concern:

Be it known that we, EDWARD LA BARRE, a citizen of the United States, and a resident of the city of New York, borough of the Bronx, in the county of Bronx and State of New York, and WILLIAM SCHUCKAR, a citizen of the United States, and a resident of West New York, in the county of Hudson and State of New Jersey, have invented a new and Improved Automatic Train-Stop, of which the following is a full, clear, and exact description.

Among the principal objects which the present invention has in view are: to provide a series of stationary signal-operating mechanisms adapted to automatically assume the position to which they have been adjusted; to provide standing signal mechanisms operable electrically or mechanically at will and in correspondence with or independent of the conventional visual or semaphore signals; to provide a signal-operating mechanism carried by a locomotive or car to set the brakes controlling the movement of the locomotive, car or train; and to provide a flexible structure adapted to avoid breakage.

In the accompanying drawings,

Figure 1 is a plan view of a fragment of a railway track bed and the pilot of a locomotive, said bed and pilot being provided with removable and stationary parts of an automatic stopping mechanism, constructed and arranged in accordance with the present invention;

Fig. 2 is a detail view on an enlarged scale, showing in vertical section a stationary stand, constructed and arranged in accordance with the present invention;

Fig. 3 is a detail view in perspective on an enlarged scale, showing a flag head of one of the station stands;

Fig. 4 is a detail view on an enlarged scale, showing in horizontal section a fragment of a station stand case box and a flexible setting and resetting mechanism;

Fig. 5 is a side view of a signal-operating mechanism and latch therefor;

Fig. 6 is a cross section on an enlarged scale taken on the line 6—6 in Fig. 5;

Fig. 7 is a top plan view of Fig. 5, showing in dotted lines the arrangement of the trigger lever when operated upon;

Fig. 8 is a vertical section on an enlarged

scale, taken as on the line 8—8 in Fig. 7; 55 and

Fig. 9 is a section on an enlarged scale, taken as on the line 9—9 in Fig. 5.

Fig. 10 is a detail view in elevation, showing the main controlling positioning block 60 with which the apparatus is provided, the dotted lines in said figure indicating the rollers for supporting a weighted member on said block, the raised and lowered position of said rollers in relation to said block 65 being indicated.

As indicated best in Fig. 1 of the drawings, a station-operating mechanism is bolted or otherwise made fast in position, adjacent the roadbed or one of the track 70 rails thereof. The casing 15, in which the station-operating mechanism is mounted, is provided with a rounded extension 16, the cap 17 whereof is bolted to the extension. The cap 17 is centrally perforated and provided with an upstanding boss 18, said boss being bored concentric with the perforation mentioned and being adapted to register with the screw threads of the lower end of a tube 19. The perforation referred to and the tube 19 are both intended as a guide and housing for the vertical shaft 20. The shaft 20 is stepped in a socket formed in a boss 21 on the base plate 22 of the casing 15.

The boss 21 is bored to form an annular flange to receive a supporting block 24. The supporting block 24 is circular. The edges are shaped to form two cam surfaces 25. The surfaces 25 are of equal length and made to form the peaks 26, which are the high points of the cams thus constructed.

The cams thus formed are provided as paths or runways for the rollers 27. The rollers 27 are pivotally mounted in bearings in the weighted cage 28 and in the solid ring portion 29 thereof. The cage 28 is supported upon the block 24 and slidably engages the vanes 30, in the casing 15 and extension 16 thereof.

The vanes 30 hold the cage 28 against 100 rotation, hence when the block 24 is rotated, the peaks 26 are moved from the position shown in Fig. 4 of the drawings to a position coincident with or adjacent to the rollers 27. In this action, the block 24 operates to lift the cage 28 a distance represented by the rise of the cam surfaces 25. When the block 24 is not held in the adjusted posi-

tion, the cage 28 operates through the rollers 27 and cam surfaces 25 to retract the said block 24 until the rollers 27 rest at the lowest points of the cam surfaces 25; or, 5 in other works, return the said block to the position shown in Fig. 4 of the drawings. It will be understood that the operation of the cage 28 insures the rotation of the block 24 and parts connected therewith to produce 10 the active condition of the vanes 47 and shaft 20 in the event that the operating connections between the block 24 and the signal system are broken or interrupted.

The block 24 operates primarily to rotate the shaft 20. The block 24 in service is held in "clear way" indicating position by a lever arm 31, pivoted at 32, and by a connecting link 33, pivotally connected at 34 at the under side of the block 24. The 15 lever arm 31 is provided with an eyelet 35, to which a connecting rod is attached. The connecting rod is not shown in the present drawings, it being understood that the rod is a part of any of the conventional mechanisms 20 at present used for operating semaphore or other standing railway signal devices. For the purpose of the present description, it will be understood that when a companion semaphore is disposed in warning or danger-indicating, position, the arm 31 is in the position shown in Figs. 1, 2 and 4 of the drawings. When the track is clear, the arm 31 is moved to the right of the position shown in Fig. 4, thereby rotating the 25 block 24 to a position where the point 26 would be coincident with, or adjacent to, the indicated position of the rollers 27.

The block 24 is centrally bored to receive loosely the lower end of the shaft 20. Concentric with and surrounding the bore for the shaft 20 in the upper surface of the block 24, a recess or cup is formed to receive the bearing balls 36, upon which is mounted a cam block 37.

40 The block 37 is moved independently of the block 24. The block 37 is centrally bored to provide a rectangular passage for the square section 38 of the shaft 20. By this method, the shaft 20 and block 37 are 45 operatively united.

The cam block 37 supports the weighted cage 39, and the cage 39 is centrally bored to freely pass the shaft 20, and is operatively connected with the block 24, by means of 50 upright guides 40. The guides 40 extend into slots 41, with which the cage 39 is provided.

The portion of the cage 39 wherein the slots are provided, is shaped to form a depending flange, which serves as a housing for the block 37. The cage 39 is in turn housed within the cage 28 by a cylindrical extension thereof, which extension is closed 60 adjacent the top thereof by a partition 42, centrally perforated to receive the shaft 20

therein as a guide therefor. From the foregoing it will be noted that the blocks 24 and 37, the rollers 27 and 43 and the cage 39 are neatly and simply nested within the cage 28, as best seen in Fig. 2 of the drawings.

70 The rollers 43 are pivotally mounted in the cage 39 in a manner similar to that employed in mounting the rollers 27 in the cage 28, and the action of the rollers 27 on the cam surfaces 25 is similar to the action 75 of the rollers 43 on the cam surfaces 44 formed in the edge of the block 37.

The cross head 45 is provided with a cap 46 and at the extremities of the arms, with the vanes 47. The cap 46 is rigidly mounted 80 at the end of the shaft 20. The vanes 47 are so arranged that when the shaft 20 is properly rotated, one of the vanes 47 will rest in the path of the trigger lever 48, carried by a locomotive or other vehicle moving over the roadbed. The operative position of the vanes 47, showing their relation to the trigger lever 48, is best seen in Fig. 1 of the drawings.

A stand constructed and arranged as described and as shown in the accompanying drawings, is operable by any of the usual and known methods. The normal position is that in which the vanes 47 rest in the path of the trigger lever 48. To this position the cages 28 and 39 automatically move the blocks 24 and 37, the shaft 20 and cross head 45 connected therewith, when the lever arm 31 is moved to the position shown in Fig. 4 of the drawings.

90 In the disposition of the vanes 47 and parts connected therewith, as above described, provision is made for striking the trigger lever 48 with a yielding blow, thus avoiding breakage of the engaging elements 95 of the moving and the stationary structures.

100 It will also be noted that the block 24 having been set in the manner described, the cross head 45 cannot be successfully tampered with, for if the said head, with the shaft 20 connected therewith, is moved out of service position to which it is set, the weight of the cage 39, operating upon the block 37, immediately and automatically causes the return of the parts to their service 110 position. The same is true of the parts when in out-of-service position.

115 The brake-setting mechanism, when constructed in accordance with the present invention, is mounted on a face plate 50. The face plate 50 may be mounted on any part of the moving vehicle. When applied to a locomotive, we prefer to mount it on the pilot frame. The setting of the brakes when operated in accordance with the present invention, is effected by bleeding the train pipe 51, a branch connection 52, uniting the same with a valve case 53, as shown best in Figs. 5 and 8 of the drawings. The valve case is provided with a discharge port 54.

Communication between the port 54 and the inlet to the valve case is normally closed by a piston valve 55 and a soft plug 56. To receive the plug 56, an inverted, conical 5 valve seat 57 is formed at the bottom of the case 53. The efficiency of the valve 55 is further augmented by packing rings 58 of any suitable conventional construction. The opening between the port 54 and the interior chamber of the case 53 is formed by an elongated slot 59. The slot 59 is bridged midway by a fillet 60 which operates to prevent the packing rings 58 from becoming dislodged from their holding grooves in the 10 piston valve.

The plug 56 is rigidly mounted on the valve 55 by a compression screw 61. The screw 61 is provided with a threaded end and a cupped flange 62. The lower face of 20 the valve 55 is provided with an annular flange 63, shaped to correspond with the flange 62, and both flanges operate to compress the material of the plug 56 toward the screw 61.

25 The valve 55 has a contracted portion or stem 64. The stem 64 is transversely pierced to receive a pin 65 by which it is coupled with a plunger 66. The stem 64 is slidably fitted or housed in a cap 67, provided for the 30 valve case 53. Oiling spaces 68 and 69 are formed above and beside the stem 64, communication between which is maintained during a portion of the stroke of the valve by a saw cut channel 70 formed in the inner 35 wall of the lower portion of the cap 67.

40 The channel 70 is shortened so that the stem 64 closes the said channel on the up-stroke of the piston valve 55 and operates to trap air contained in the spaces 68 and 69 to form a cushion for the piston valve 55. This operation is not interfered with by any lubricating oil which may be present in either of the said spaces.

45 The valve 55 is lifted by the pressure of the brake operating air in the train pipe and branch 52 thereof. Normally, the said valve and the plug 56 are maintained in closed relation by a latch arm 71. The arm 71 is pivoted on the face plate 50 and upon a 50 bolt 72. The arm 71 is provided with a short arm 73. The arm 73 is pivotally connected with a rocking lever 74, which is pivoted on the bolt 75 on the plate 50. The lever 74 is bifurcated at one end to enfold 55 the end of the arm 73 and to hold the pin 76 and a roller mounted thereon. The said roller is disposed in an elongated slot 77, with which the arm 73 is provided. This construction is best shown in Fig. 5 of the 60 drawings. The opposite extension of the lever 74 is similarly engaged with the plunger 66 by means of a pin 78 and roller thereon in a slot 79.

65 In service position, or when the plunger 66 and valve 55 connected therewith are

lowered to close the port 54 of the valve case 53, the latch arm 71 is held in the position shown in full lines in Fig. 5, by the trigger lever 48. The lever 48 fits in a groove formed in the end of the latch arm 71, as 70 best seen in Figs. 5 and 7 of the drawings. The pressure exerted through the valve 55, plunger 66 and lever 74, upon the latch arm 71 is such as, unrestrained, would lift the said latch arm and parts connected therewith, to the position shown by dotted lines in Fig. 5 of the drawings. The upward stress thus maintained on the latch arm 71 holds the end of the said lever having a 75 groove 80, in locked engagement with the 80 trigger lever 48. When in the course of operation, the lever 48 engages one of the vanes 47 and is forced backward thereby to the position shown by dotted lines in Fig. 7 of the drawings, the said trigger lever disengages the latch arm, and the said latch arm and parts connected therewith are permitted to assume the position shown by dotted lines in Fig. 5 of the drawings. This 85 position is readily effected by the pressure 90 of the air in the train pipe and branch 52 thereof, which lifts the piston valve 55 until the slot 59 is exposed and the air from the train pipe and branch 52 thereof is permitted to escape to the outer atmosphere, 95 reducing the train pipe pressure and operating the triple valves of the brake-setting mechanism.

100 It is to provide a buffer for the trigger lever 48 that we provide jaws 81, shown best in Fig. 9 of the drawings. The pivot shaft of the lever 48 is provided with a wedge 82, which, when the lever 48 is thrown back by engaging the vanes 47, assumes the position shown by dotted lines in Fig. 7 of the drawings, where the contracted edge of the wedge 105 is forced between the jaws 81.

110 The jaws 81 are pivoted by pins 83 on brackets 84, and are provided with tail extensions 85, between which is held a rubber jack 86, or other suitable compression spring. The jack 86 is held in position by a pin 87, as shown in Fig. 9 of the drawings. The ends of the jaws are inclined, as best shown in Fig. 7 of the drawings, to accommodate 115 the throw of the wedge 82.

120 The trigger lever 48 is held in operative position by bolts 88, which set up the clamp plates 89 to grip the inner end of the said lever. To avoid the breakage of the trigger lever 48, but to insure its breaking at such a place as to release the arm 71, in the event of breakage, a yielding section 90 is formed by reducing the material at the point indicated in Figs. 5 and 7 of the drawings. 125 From the above, it will be seen that the tendency to break the lever 48 is largely overcome, and also that, in the event that a lever is broken, it may be readily and quickly replaced.

As customary in systems of a similar character, the controlling stations are operated to set the vanes 47 in position to engage the lever 48, in the event that a train thus 5 equipped attempts to run by the station when so set. If such a contingency arises, the lever 48 is forced out of engagement with the latch arm 71 and the brakes are applied to the train in the manner as above 10 described. This operation is beyond the control of the engineer or driver, the mechanism being disposed at a position on the locomotive inaccessible for him. After the brakes have been automatically set, the 15 engine and train carried thereby cannot proceed until the latch arm 71 is placed in the position shown in full lines in Fig. 5 of the drawings, to close the valve 55. The lever 48 is then moved to engage the latch arm 71 20 and the groove 80 therein, to hold the same and the valve 55 connected therewith in service position and ready to be operated upon by a succeeding station, should the engine be again run by the danger or caution 25 signal.

As may be seen in the drawings, the cap 46 is provided with hinge knuckles 91 and hooks 92. This construction is provided to 30 permit the placement on the cap, of a lantern to be used in conjunction with the stand.

Also, it will be understood that the space 35 between the wall of the extension 16 and the cage 28, above the ring portion 29 thereon, permits the introduction thereon of additional weights, the purpose being to make the operation of the cage on the block 24 more positive if required. The same arrangement is provided between the inner 40 walls of the cage 28 and the neck of the cage 39, which may also be provided with auxiliary or added weight members.

Claims:

1. An apparatus as characterized, comprising a rotary shaft; a cross head rigidly mounted on said shaft; interference members mounted at the ends of said cross head; a rotary block for supporting said shaft, said block having upwardly turned cam surfaces; a weighted cage supported on said block and embodying rotary members to track on said cam surfaces for rotating said block to its adjusted position; means for guiding said cage to move in a vertical direction; means loosely connecting said block and shaft to move in unison; and means 55 remotely operative to rotate said block.

2. An apparatus as characterized, comprising a rotary shaft; a cross head mounted on said shaft; interference members mounted on the ends of said cross head; a rotary block rotatively supporting said shaft and provided at the edge thereof with upwardly turned cam surfaces; a weighted 60 member having roller supports to track on

said cam surfaces for rotating said block to its adjusted position; a fixed structure forming guides for said weighted member to move the same in a vertical direction; a cam block fixedly mounted on said shaft in superposed relation to said rotary block, 70 said cam block being provided with a plurality of cam surfaces upwardly turned; a minor weighted member having rolling supports to track on the cam surfaces of said cam block; guides operatively connecting said cam block and minor weighted member to guide the movement of said minor weighted member; and means operatively remote for revolving said rotary block. 75

3. An apparatus as characterized comprising, a signal vane; a supporting shaft therefor rigidly attached thereto; a cam block for supporting said shaft, said block having upwardly-acting cam surfaces, said surfaces being disposed at opposite sides of said block; a supporting block for normally supporting the said cam block, said supporting block being provided with upwardly-acting cam surfaces, similar in character to the cam surfaces of said cam block; a weighted member operatively connected with said supporting block for maintaining its alinement therewith, said member being free to move vertically above said supporting block; rolling means interposed between said member and said cam block for supporting said member on said block; a stationary casing for said block and parts connected therewith, said casing having vertically disposed guide members; a weighted cage surrounding said weighted member and said blocks, said member being free to move vertically in said casing and above said supporting block; rolling means interposed between said supporting block and said cage for tracking on the cam surfaces of said block for normally maintaining said supporting block in constant relation to said casing and guide members therein; and means operable at a distance from said casing for rotating said supporting block. 90

4. An apparatus as characterized comprising, a signal vane; a supporting shaft therefor rigidly attached thereto; a cam block for supporting said shaft, said block having upwardly-acting cam surfaces, said surfaces being disposed at opposite sides of said block; a supporting block for normally supporting the said cam blocks, said supporting block being provided with upwardly-acting cam surfaces, similar in character to the cam surfaces of said cam block; a weighted member operatively connected with said supporting block for maintaining its alinement therewith, said member being free to move vertically above said supporting block, means interposed between said member and said cam block for supporting said member on said block; a stationary 100

130

casing for said block and parts connected therewith, said casing having vertically disposed guide members; a weighted cage surrounding said weighted member and said blocks, said member being free to move vertically in said casing and above said supporting block; means interposed between said supporting block and said cage for tracking on the cam surfaces of said block for normally maintaining said supporting block in constant relation to said casing and

guide members therein; and means operable at a distance from said casing for rotating said supporting block.

In testimony whereof we have signed our 15 names to this specification in the presence of two subscribing witnesses.

EDWARD LA BARRE,
WILLIAM SCHUCKAR.
